UNITED STATES PATENT OFFICE.

FREDERIC STANTON PERRIN, OF NEW YORK, N. Y.

CARBURETER.

1,044,569.

Specification of Letters Patent. Patented Nov. 19, 1912.

Application filed October 12, 1909. Serial No. 522,282.

To all whom it may concern:

Be it known that I, FREDERIC STANTON PERRIN, a citizen of the United States, and a resident of the city of New York, in the 5 county of New York and State of New York, have invented certain new and useful Improvements in Carbureters for Internal-Combustion Engines, of which the following is a specification.

10 My invention relates to improvements in carbureters for internal combustion engines, and the objects of my improvements are, first, to transform volatile fluids, such as gasolene, into a gaseous state; second, to 15 atomize non-volatile liquids, such as kerosene, and transform them into an aeriform elastic fluid; and, third, to increase or decrease, at will, the supply of the fluid to be transformed. I attain these objects by the 20 mechanism illustrated in the accompanying drawing, in which—

Figure 1 is a vertical section of the entire carbureter; Figs. 2, 3 and 4 are views of a movable plate resting upon the nozzle at 25 different positions, and Fig. 5 is a detail of the nozzle.

Similar numerals refer to similar parts throughout the several views.

In Fig. 1 the numeral 1 represents a fluid 30 reservoir having a float 3, operating the valve 4, in the supply pipe 5, to prevent the over-flowing of the fluid; 2 is the gas chamber connecting with the passage 18, leading to the engine cylinder and an auxiliary air 35 chamber 20, which is closed by the valve 15; 8 represents a nozzle having an opening 7, connecting with the duct 6, leading from the reservoir 1; 9 is a plate resting upon the nozzle 8, with an aperture 16, shown in Figs. 40 2, 3 and 4, to which plate is attached a U shaped rod 11; 13 is a prolongation of 11, attached to the lever 14; 12 is the air intake chamber through which the main air enters; and 17 is the inlet through which the 45 auxiliary air enters the valve chamber 20.

In Figs. 2, 3, 4 and 5 the numeral 10 represents a narrow longitudinal vent in the nozzle 8. The broken line 19 represents the level of the fluid maintained by the float 3, in the reservoir 1, by means of the valve 4.

The operation of the carbureter is as follows: Fluid from a supply tank (not shown in the drawing) enters the opening 5, and flows into the reservoir 1, until the float 3 55 rises and closes the valve 4, when its level reaches the broken line 19. This fluid passes

through the duct 6, up through the opening 7, in the nozzle 8, to a short distance below the nozzle vent 10, as shown by the line 19. The engine cylinder (not shown) is connected with the passage 18 by means of a tube, in such a manner that the moving of the piston, within its cylinder, draws air through the main inlet 12, over the nozzle vent 10, through the aperture 16, in the plate 9. This plate may fit closely against the wall of the inlet chamber 12, and rotates adjacent and preferably upon the nozzle 8, practically closing the passage through chamber 12 except at the aperture 16 of plate 9. As this air passes over the nozzle vent 10, it creates a partial vacuum in the nozzle and draws up the fluid through the vent 10. When the fluid rises above the vent, the air picks it up and transforms it into a fine spray, which is carried into the cylinder in a gaseous state, if the fluid is volatile, or an aeriform elastic fluid, if the fluid is non-volatile.

The plate 9 has the aperture 16 at its 50 center a little shorter than the length of the nozzle head, to prevent the nozzle from passing through the aperture, and considerably wider than the width of the nozzle head. This plate is movable upon the nozzle by 55 means of the lever 14, rod 13, and U shaped rod 11. Fig. 4 shows the aperture 16 at right angles with the vent 10, exposing a small portion of the vent; Fig. 2 shows the plate 9 moved to an angle of forty-five degrees, exposing a greater portion of the vent; and Fig. 3 shows the plate moved to a position placing the aperture parallel with the vent, and exposing its full length. It 60 will be seen, by this means, I am enabled to 90 expose any portion of the vent to the incoming air, and allow the air to draw up fluid according to the portion of the vent exposed by the aperture 10. The bottom of the plate 9 rests upon the nozzle and closes the vent 10 at all points except opposite the aperture 16.

The auxiliary air valve 15 is set, by the tension upon its spring, to open by the suction of the piston and take in sufficient air 105 to mix with the fluid spray and form a proper explosive mixture in the cylinder.

With the nozzle shown in Fig. 5 the longitudinal vent 10 is gradually increased or decreased by moving the aperture 16 and 110 lengthening or shortening the exposed portion of the vent.

The supply of fluid may be increased or decreased at will by simply changing the position of the aperture in the plate 9 with respect to the nozzle, the flow of air through 5 aperture 16 of plate 9 likewise being controlled by the position of said aperture with respect to the nozzle.

I am aware that prior to my invention air has been drawn, by means of an engine 10 piston, over the vent of a nozzle in a carbureter. I, therefore, do not claim such a combination broadly; but

What I do claim as my invention, and desire to secure by Letters Patent, is—

15. 1. In a carbureter having an air chamber open at opposite ends, a nozzle, leading from a fluid reservoir, formed at its outlet with a narrow longitudinal vent, said nozzle being located between the open ends of said 20 chamber, a plate fitted in said chamber upon the nozzle and rotative thereon in the chamber, said plate having a perforation longer than wide and wider than the top of the nozzle.
25. 2. In a carbureter, a nozzle, leading from a fluid reservoir, formed at its outlet with a narrow longitudinal vent; and a plate having a perforation wider than the top of the nozzle adapted to move upon the nozzle in

a manner to close the vent at all points 30 except opposite the perforation, the latter being arranged to permit the flow of air therethrough, substantially as described.

3. A carbureter comprising a nozzle, leading from a fluid reservoir, formed at its outlet with a narrow vent, and a plate having a central perforation wider than the top of the nozzle adjacent and coacting with said vent to control the flow of fluid from said vent, said perforation being arranged to permit the flow of air therethrough past the nozzle.

4. A carbureter having a chamber, a nozzle within said chamber having a vent longer than wide, a plate having an aperture longer than wide and wider than the top of the nozzle, to coact with said vent, and means to move one of said parts relatively to the other to vary the portion of the aperture over the nozzle.

Signed at the city of New York in the county of New York and State of New York this 11th day of October, A. D. 1909.

FREDERIC STANTON PERRIN.
